UNITED STATES PATENT OFFICE.

OSCAR SANDBERG, OF BATTLE CREEK, MICHIGAN, ASSIGNOR TO JOHNSON AUTOMATIC SEALER CO., LTD., OF BATTLE CREEK, MICHIGAN, A PARTNERSHIP ASSOCIATION, LIMITED.

WRAPPING MACHINE.

Application filed January 23, 1923. Serial No. 614,447.

The present invention is an improvement in wrapping machines, particularly of the type used for wrapping bread. The objects of the invention are, generally, to provide a cheap, durable and efficient device of this character which may be readily and simply manufactured, operated and repaired, which has a large output and which operates to wrap and seal a wrapper, preferably of waxed paper, around the bread smoothly and closely.

The invention will be better understood by reference to the accompanying drawings, in which—

13. Fig. 1 is a side elevation of the machine;
- Fig. 2 is an end elevation of the machine;
- Fig. 3 is a perspective view showing particularly the mechanism for introducing the loaves into the machine;
20. Fig. 4 is a perspective view showing the pusher for removing the loaves from one of the conveyors onto the elevator, and also the detector mechanism;
- Fig. 5 is a detail view of the detector mechanism;
25. Fig. 6 is a perspective view showing the paper feed;
- Fig. 7 is a detail view of the supporting fingers that bridge the space above the elevator as the wrapping paper is fed forward;
30. Fig. 8 is a longitudinal sectional view through the upper part of the machine showing the general arrangement of parts, some of the parts being omitted;
35. Fig. 9 is a detail of the paper-cutting mechanism;
- Fig. 10 is a detail of the feed for the first intermittent conveyor;
- Fig. 11 is a perspective view of the first 40 folder and the second reciprocating carrier;
- Fig. 12 is a perspective view showing the arrangement of the heating elements;
- Fig. 13 is a perspective view showing the folder for the rear bottom flap and the folder for the second or rear end flap;
45. Fig. 14 is a perspective view of the folder for the second or rear end flap;
- Fig. 15 is a pulled-out view showing the means for operating this folder;
50. Fig. 16 is a detail showing a gravity pressure device that rests on the loaf as it is being wrapped and also while it passes through the heaters;
- Fig. 17 is a perspective view showing par-

ticularly the means for feeding the sheets of paper forwardly to be wrapped, and also the fingers for supporting and forming the lateral marginal extremities of the wrapper on the loaf;

Fig. 18 is a perspective view of the first reciprocating carrier that progresses the loaf from the elevator to a position between the first set of heaters;

Fig. 19 is a diagrammatic view indicating a loaf of bread at various stages of the operation of wrapping and sealing; and

Fig. 20 is a perspective view showing the second reciprocating conveyor.

Referring to the drawings, wherein like reference numerals indicate like parts, 30 is a conveyor on which the loaves of bread are deposited either manually or automatically and from which they are delivered onto the second conveyor 31 which latter is arranged at right angles to the first conveyor 30. Both of these conveyors are preferably driven intermittently. The conveyor 30 is driven from shaft 31' through arm 32, link 33, and arm 34 (Fig. 10) carrying a spring-pressed pawl 35 that engages a ratchet 36 on shaft 37 carrying a pulley 38 about which the belt or conveyor 30 passes. The conveyor 30 also passes around a pulley 38' on shaft 30'.

The conveyor 31 is driven from a motor 39 through a belt 40, shaft 41, belt 42, clutch shaft 43 and cam shaft 44. The cam shaft 44 is driven from clutch shaft 43 through a sprocket chain 45 engaging a sprocket 46 on shaft 43 and sprocket 47 on shaft 44. A sprocket 48 is mounted on shaft 44 and a sprocket chain 49 passes around said sprocket 48 and also around the sprocket 50 on the shaft 51. This shaft 51 drives shaft 31' through gears 52 and 53, and, as here shown, the conveyor 31 is driven intermittently from shaft 31' through a crank 55 mounted on said shaft 31' connected to a link 56 one end of which is secured to one arm of a bell-crank lever 57 pivoted at 58. The other arm of this bell-crank lever is connected to one end of a link 59, the other end of which link is connected to the free end of an arm 60 loosely mounted on shaft 61. This arm carries a spring-pressed plunger 62 one end of which plunger engages a series of lugs 63 formed on a sprocket wheel 64 around which passes a sprocket chain 65, which lat-

ter also passes around a sprocket 66 carried on a shaft 67 which shaft also carries a second sprocket 68 about which the conveyor 31 passes. This conveyor 31 also passes 5 around a sprocket 69 carried by a shaft 70. Said conveyor 31 is preferably provided with flights or pushers 70' that receive the loaves from conveyor 30 and progress the same forwardly on tracks 31" to the position 10 where they are delivered to the elevator. In order to prevent over-movement of the conveyor 31, a two-part brake 70^a is secured to the frame at 70^b and passes around shaft 70, the two parts being pressed into yielding 15 engagement with said shaft by spring 70^c.

Each succeeding loaf is removed from the tracks 31" onto the elevator 71 (Figs. 6 and 8) by pusher 72 (Fig. 4) and is positioned on said elevator by engagement with spring 20 plates 71^a and 71^b. Said pusher is carried by an arm 73 secured to the upper end of an arm 74 pivoted at 75. The reciprocating movements transverse of conveyor 31 are imparted to the pusher 72 by a parallel link 25 motion constituted by a shaft 76 and arms 77 and 78. The arm 77 is connected to arm 73, and the arm 78 is moved backward and forward by a cam 79 mounted on shaft 31', said cam engaging a roller 80 carried by one 30 arm of a bell-crank lever 81 pivoted at 82 to the frame of the machine. The other arm of said bell-crank lever 81 is connected to the arm 78 by a link 83. The arm 78 is provided with a plurality of holes or openings 35 for the reception of one end of the link 83 so as to vary the extent of movement of the pusher 72.

The elevator 71 is raised and lowered by a cam 85 (Figs. 6 and 11) mounted on a 40 shaft 44 and operating through a lever 86 pivoted at 87. One arm of said lever carries a roller 88 that engages said cam and the other arm of said lever carries a link 89 that is connected to the body of said elevator.

As the loaf of bread is raised by said elevator, a measured size of wrapping paper is fed across the path of movement of said loaf. As shown particularly in Fig. 6, the 50 paper is carried in a roll 90 supported on brackets 91 and 92. The web of paper is fed forwardly under roller 93, thence over roller 94, thence under roller 95, thence under the paper-severing blade 96 mounted on a shaft 97. The rollers are driven through a sprocket chain 98 passing around a sprocket wheel 99 (Fig. 3) carried by shaft 44 and also around a sprocket 100 carried by shaft 101. On the far end of said shaft 101 55 is mounted a pinion 102 that meshes with an idler 103 that meshes in turn with a pinion 104 mounted on shaft 105. On said shaft 105 is mounted a second pinion 106 that meshes with a pinion 107 on the shaft that 60 carries the roller 95. Shaft 97 that carries

the cutter blade 96 is provided with a gear 108 that meshes with a pinion 109 mounted on shaft 101.

The sheet of paper as it is severed is fed forward by means of a plurality of belts 70 110, 111, 112 and 113 (Fig. 17). All of these belts pass around pulleys mounted on shaft 114 and belts 110 and 113 also pass around pulleys on shaft 115 while belts 111 and 112 pass around pulleys on shaft 116. 75 These belts are driven from shaft 44 (Fig. 3) through sprocket chain 44^a that passes around sprocket wheel 44^b on shaft 44 and around a sprocket 31^a on shaft 31'. This sprocket 31^a is carried by a sleeve 31^b loose 80 on shaft 31' and said sleeve also carries a sprocket wheel 31^c around which passes a sprocket chain 115' that drives shaft 115 through sprocket 115^a.

The sheet as it is fed forward is controlled 85 in its movement by rollers 117 and 118 (Fig. 6) that bear upon the upper surface of the paper, wires 119 arranged above the surface of the sheet, and spring fingers 120 that press lightly on the sheet. The sheet is fed across the path of the loaf on the elevator and is positioned by the front edge thereof engaging a paper stop 121. As the sheet 90 engages this stop, the loaf of bread being raised by the elevator is pressed against the under side of the sheet and the continued elevation of the loaf against the sheet causes the paper to be wrapped over the top and down the front and rear of the loaf, as indicated at position "5", Fig. 19. 100

In order to prevent the laterally projecting portions of the wrapper from breaking as the loaf is pressed against the sheet, curved fingers 122 and 123 (Fig. 17) are provided to engage the under surface of the sheet adjacent the ends of the loaf and to move upwardly with the loaf and the sheet for a limited distance until the shape of the laterally projecting ends of the wrapper has been established. These fingers 122 and 123 110 are mounted on a shaft 124 that is provided with an arm 125, the free end of which is connected to one end of a link 126, the other end of which link is connected to one arm of a lever 127 pivoted at 128. This lever carries a roller 129 that is pressed against a cam 130 mounted on shaft 31', by a spring 131. A spring 132 is connected to arm 125, with the result that the fingers 122 and 123 115 are positively elevated by the cam 130 for a limited distance and are retracted by the spring 132. 120

The first end fold (see position "6", Fig. 19) is made while the loaf is carried by the elevator, and the mechanism for effecting this first end fold is in the form of a pair of folding blades 133 and 134 (Fig. 11), each of which blades is pivoted at 135 on a carriage 136 that is vertically reciprocated on a standard 137. The two carriages are con- 130

neected by a rod 138 mounted in brackets 139 and 140 on said carriages 136. These carriages are elevated and depressed through links 141 and 142, the lower ends of which are connected to the free end of arms 143 and 144 mounted on shaft 145. This shaft carries an arm 146 to which is connected one end of link 147, the other end of which is connected to the lever 86 that operates the elevator. From the connections described, it will be seen that as the elevator is raised the fold blades 133 and 134 will be lowered to effect the first fold as shown in position "6", Fig. 19. The continued elevation of the loaf leaves it between fingers 148 and 149 on the one hand and 150 on the other (Figs. 11 and 20). These fingers 148 and 149 are rigidly secured to rod 138 whereas finger 150 is loosely pivoted thereon and is provided with a projection 151 to which is secured one end of a spring 152, the other end of said spring being anchored to a yoke 153. This resilient mounting of the finger 150 permits of an automatic adjustment that is desirable on account of variation of size of the loaf.

As the loaf is elevated between these fingers and as the first fold is completed and just before the elevator starts downward and the blades 133 and 134 start upward, the loaf is pressed against fingers 148 and 149 by additional fingers 154 and 155 (Figs. 1, 3 and 8) mounted on shaft 156. This shaft carries an arm 157, the free end of which is connected to one end of a link 158, the other end of which link is connected to an arm 159 carried by shaft 160. This shaft 160 carries an arm 161, and is rocked through link 162, lever 163 loosely mounted on shaft 31' and roller 164 which engages the cam 165 mounted on shaft 44.

While the loaf is clamped between the fingers 148 and 149 on the one hand and 154 and 155 on the other, the rear bottom fold is effected by a plate 166 as shown in Fig. 13. This plate is carried by a pair of rods 167 passing through bearings 168 and connected at one end to arms 169 pivoted at 170. A link 171 is connected at one end to one of said arms and at the other end to an arm 172 secured to shaft 173 which latter carries a second arm 174 provided with a roller 175 that engages a cam 176. As the plate 166 moves forward to position "7" of Fig. 19, and makes the rear bottom fold, the folders for the second or rear end flap come into operation. These folders are indicated at 177 and 178 and are mounted on arms 179 and 180 carried in turn by rod 181. This rod has secured thereto an arm 182, the free end of which carries a roller 183 that engages a cam slot 184 in a casting 185 (Fig. 15). This cam slot has a horizontal run 186 and a vertical run 187, so that the folders 177 and 178 will not only move forwardly to make

the second or rear end fold which is shown completed in position 8 of Fig. 19, but will also have a downward movement which will cause the horizontal part 177' of each of said folders to sharply crease the folds that have just been made. It is to be noted that this fold has been effected while the loaf was resting on the rear bottom flap folder 166.

The first and second end flaps and the rear bottom flap having been completed, the loaf is ready to be advanced, and this movement of the loaf from the blade 166 is effected by means of a reciprocating pusher or carrier 188 (Figs. 8 and 18) mounted on an arm 189 sliding in bearings 190 (Fig. 18). This arm 189 is moved backward and forward from shaft 44 through the medium of cam groove 191 in cam 85 mounted thereon. This cam groove is engaged by a roller 192 carried in the end of arm 193 secured to shaft 194 which shaft is provided with a second arm 195 to which is secured one end of a link 196, the other end of which is connected to a lever 197 pivoted at 198. The other arm of said lever is connected to one end of a link 199, the other end of which link is secured to arm 189.

The pusher 188 is provided with two similar side members 200, each of which is adjustable laterally on the pusher 188 by means of a pin and slot connection 201, so that the pusher may be varied in size dependent upon the particular size of the loaf being wrapped. Each of these side members 201 is provided with a plurality of fingers 202 which engage and press upon the second end flap after it has been completed and creased, as shown at position "8" of Fig. 19. Each end member 200 is also provided with a smoother 203 that engages the upper rear corner of the wrapper on the loaf. As the pusher 188 is moved forward, it forces the loaf with the wrapper past the front edges of a pair of heating plates 204 (Fig. 12) suitably supported on the machine frame. The edge 205 of each of these heating plates acts as a stationary folder and effects the folding of the third end flap as the loaf is forced into position between the said heating plates 204. Position "8", Fig. 19, shows the third end flap about to be engaged with the stationary folder, and position "9", Fig. 19, shows the wrapper with the third end flap completely folded. In order that the fingers 202 may hold the second rear end flap securely against the loaf and in order that the third end flap, after it has been folded by the edge 205, may be pressed down close upon the second end flap and also insure that heat shall be applied not only to the third end flap but also to the second end flap, recesses 206 (Figs. 8 and 12) are provided in heating plates 204, which recesses receive the fingers 202. The heat is applied to the second and third end folds through the portions 207 of the plate

204 intermediate said recesses 206 for the purpose specified.

The loaf with the first, second and third end flaps completed is finally deposited by the pusher 188 between the heating plates 204, and all of these folds are securely fixed together, when waxed paper is used, by the melting of the wax on the paper. The loaf is now ready to be moved forward for the purpose of completing the sealing and delivering of the same, and for this purpose a second reciprocating carrier is provided which moves the loaf from between the first pair of heating plates 204, past the stationary folder for effecting the fourth or final end fold and between a second pair of heating plates for the end flaps. As here shown this carrier (Figs. 11 and 20) is in the form of a carriage which is reciprocated longitudinally on rods 208, one end of which are fixedly secured to sleeves 209 mounted on rod 138. This carrier comprises a pair of sleeves 210 that are connected together by rods 211 and 212. On these rods are carried a plurality of depending fingers 213, 214 and 215, here shown as three. The fingers 213 and 215 are longitudinally adjustable with respect to finger 214, in order to move them closer together or further apart to accommodate loaves of different sizes, and this is effected by pin and slot connections 213' and 215'. The carriage is reciprocated by a link 216, one end of which is connected to rod 212 and the other end of which is connected to a free end of an arm 217 (Fig. 1) mounted on shaft 160. The rocking of the arm 217 through the connections heretofore described effects the movement of this carriage longitudinally of the machine. In view of the fact that the rods 208 are mounted on the vertically movable carriages 136, this secondary carrier is elevated and depressed through these connections.

The loaf being deposited by the pusher 188 between the first pair of heating plates 204, the secondary carrier is lowered and the loaf is engaged between the fingers 213 and 214 in what may be designated compartment A. Through the connections described, the loaf is then progressed into an intermediate position between the first set of end heating plates 204 and the second set of end heating plates 218. The secondary carrier is then elevated, leaving the loaf in this intermediate position and with the final end fold yet to be completed. At this point a finger 216' mounted on the frame engages the second and third end folds to hold them securely in place, as shown in position "10", Fig. 19. The secondary carrier is then reciprocated rearwardly to receive another loaf in said compartment A. When it is lowered to engage the second loaf in said compartment A, the first loaf is received between fingers 214 and 215 in what may be

designated as compartment B. The carrier then moves forward, and the loaf in compartment B is progressed past stationary end folders 217 (Figs. 12 and 19) which effects the folding of the last end flap, as shown in position "11", Fig. 19, and the wrapped loaf is then deposited between the second set of heating plates 218, which thoroughly heats the last end flap and securely fixes it in place. 75

Referring particularly to Fig. 12, and to position "10" of Fig. 19, it will be observed that heating plates 219 are provided immediately beneath the intermediate position between end heaters 204 and 218. These bottom heaters 219 operate to effectively seal the seam along the bottom of the loaf in the great majority of cases, but it has been experienced that sometimes such heating is not sufficient, particularly in case the bottom of the loaf is slightly concave. There has therefore been provided a bottom heater 220 which engages the bottom of the loaf while the ends of the loaf are between the heating plates 218. This heater 220 is preferably in the form of a roller and is crowned longitudinally of its length, and means are provided for oscillating said roller to press the crowned surface thereof into intimate engagement with the paper along the bottom sealing lap. This oscillation of said roller 220 is effected from shaft 160 (Fig. 3) through a slotted arm 221, link 222, and arm 223 which latter is mounted on the rod 224 that carries the roller 220. 100

As the sealing of the end and bottom flaps and seams has been effected, the loaf is then removed, upon the succeeding reciprocation of the carrier, from between the heating plates 218 to a position between the delivery belts 225, and are carried by them to any desired point. These delivery belts preferably pass around pulleys 226 on vertical shaft 227 which are driven through beveled gears 228 and 229 from shaft 230. This shaft 230 is driven from shaft 31' through a sprocket chain 231 passing around sprocket wheels 232 and 233. In order that the delivery belts 225 may be driven at the same speed as that of the secondary carrier when the loaves first pass between the delivery belts, so that there will be no rubbing or relative movement between the loaves and the delivery belts, the gears 52 and 53 (Fig. 3) are preferably eccentric gears, to the end 115 that, when the loaves are subject to the influence of the delivery belts, the speed of movement of the belts, and accordingly of the loaves, will be decreased so that the loaves may remain for a longer period between said belts so that the sealing will be more perfect. 120

The machine is preferably provided with a paper control mechanism so that, if no loaf is present to be wrapped, no paper will be 125 130

severed or fed forward into wrapping position. This is effected by any suitable or usual means, preferably that shown and described in Johnson Patent No. 1,270,416, dated June 25, 1918. As here shown (Fig. 4) a detector finger 234 projects into the path of the loaves on conveyor 31. If a loaf is present, the shaft 235 will be rotated and, through arm 236, the link 237 will be lowered and a dog 238 connected thereto and pivoted at 239 on a lever 240 which in turn is pivoted at 241, will be lowered in front of one arm 242 of a bell-crank lever pivoted at 243. The lever 240 is provided with a roller 244 that is engaged by a cam 245 which is fastened on shaft 44. Accordingly, when said lever is rocked forward and the dog 238 is lowered in front of the bell-crank, the latter will be rocked so that its arm 245 is moved out of the path of a pawl 246 which is pivoted on a disk 247 carried by a sleeve loosely mounted on shaft 44. This sleeve also carries sprocket wheel 99 around which passes the sprocket chain 98 that drives the paper feed mechanism. This pawl 246 is adapted to engage a tooth 249 formed on a disk 250 fast on said shaft 44. The rocking of the bell-crank out of the path of pawl 246 permits the clutch to remain closed and the paper drive and cutting mechanism to be operated. If no loaf is fed and the bell-crank is permitted to remain in the path of pawl 246, the latter will be moved so that it will not engage tooth 249 and accordingly the paper drive will not be operated. The dog 238 is normally held elevated by a counter-weight 238' carried by an arm 235' on shaft 235.

At the time the sheet of paper is fed across the path of movement of the loaf on the elevator, it is desirable, if not necessary, that the fed edge of the sheet be supported in passing over this gap. Accordingly, there is provided in connection with this paper feed mechanism a bridging member (Fig. 7) which is reciprocated forwardly across the gap above the elevator as the sheet passes over said gap, and thus supports said sheet at that time. This bridging member is in the form of a slide 251 provided with a pair of fingers 252 and 253. Said slide is supported and moves in a bearing 254 and is reciprocated from main cam shaft 44 (Fig. 18) through cam 85, roller 192, arm 193 on shaft 194, said shaft carrying a lever 259 to the free end of which is connected a link 260 that is connected with said slide 251.

In order to more effectively control and position the loaf as it passes between the heating plates, there is provided a yielding member that rests upon and bears on the top of the loaf when it is subject to the heat of plates 204. This member, as here shown, is in the form of a pair of longitudinally arranged light metal strips 261 and 262 connected

by a cross-piece 263. These strips are resiliently supported at their ends nearest the delivery from a cross-bar 264 carried by standards 265. Pins 266 are secured to strips 261 and 262 and pass through openings in said cross-bar 264, said pins carrying coiled springs 267 that act to press the member yieldingly toward the loaf. At the ends nearest the elevator, said strips 261 and 262 are connected to supports 268 and 269 carried by the frame. Additional springs 270 may press on the cross-piece 263, and the latter is provided with a curved spring tongue 271 that bears on the top of the loaf while it is between the heating plates 204, this tongue acting to position the loaf and press it yieldingly against the support along which it is progressed. These strips 261 and 262 also act to support the bearings for shaft 156 (Fig. 8). 85

The machine may be turned over by hand by rotating shaft 44 through wheel 272 (Fig. 3) mounted on shaft 273 carrying sprocket wheel 274 around which passes chain 275 that also passes around sprocket wheel 276 on shaft 44. And the machine may be controlled from either side through clutch 277 carried on clutch shaft 43 through clutch lever 278 pivoted at 279. This lever may be moved either through link 280 and hand-piece 281 or link 282 and lever 283 pivoted at 284. 90

From the foregoing description of the construction and operation of the device, it will be appreciated that there has been provided a simple, cheap and efficient structure that operates to automatically and effectively wrap and seal loaves or the like at high speed. 100

While for the purpose of explanation, one expression of the inventive idea has been illustrated and described, it is to be understood that the invention is not limited thereto, and that the inventive idea may be embodied in various mechanical expressions within the limits of the appended claims, and that the device may also be used in the wrapping or wrapping and sealing of other articles; and, further, that where in the claims reference is made to "loaves", it is to be understood that this language is to be interpreted as applying equally to any other article to be wrapped. 110 115

What is claimed is:—

1. In a device of the character described, a source of paper supply, a vertically movable elevator, means for feeding a predetermined size of paper over said elevator, and a bodily movable bridging member reciprocable across the elevator space to support the paper as it is fed across said space. 120 125
2. In a device of the character described, a source of paper supply, a vertically movable elevator, means for feeding a predetermined size of paper over said elevator, and 130

a reciprocating member movable into and out of bridging relation with said elevator space.

3. In a device of the character described, 5 a source of paper supply, a vertically movable elevator for the loaves or the like, means for feeding a predetermined size of paper above said loaf as it is being elevated, means engaging a projected portion of said sheet 10 at its underside to support the same as the loaf and sheet thereon are elevated, intermittently operating means for moving said sheet supporting means upwardly, and a spring for moving said sheet supporting 15 means downwardly.

4. In a device of the character described, a vertically reciprocating elevator, a source of paper supply, means for feeding a measured size of paper over the loaf on said elevator, folders operating to fold the first end flap and the rear bottom flap practically simultaneously, folding mechanism operating to fold a second end flap while the loaf rests on the bottom folder, and stationary folders 25 to fold the third and fourth end flaps.

5. In a device of the character described, a vertically reciprocating elevator, a source of paper supply, means for feeding a measured size of paper over the loaf on said elevator, vertically reciprocating folders operating to fold the first end flap while the loaf is on the elevator, a rear bottom flap folder operating substantially simultaneously with said vertically reciprocating folders, 30 forwardly and downwardly moving folders for the second end flap, and stationary folders for the third and fourth end flaps.

6. In a device of the character described, a vertically reciprocating loaf-elevator, means for feeding a wrapper in position over the loaf on said elevator, means for folding rear end flaps, a rear bottom flap and a front bottom flap of the wrapper on said loaf, means operating after folding of the 40 rear end and the rear bottom flaps to feed the loaf forwardly through the machine from the elevator and past the front bottom flap folding means, front end flap folders provided with heating means and between which the loaf is delivered, and bottom end flap folders provided with heating means and between which the wrapped loaf is subsequently delivered and finally sealed. 45

7. In a device of the character described, a vertically reciprocating elevator, a source of paper supply, means for feeding a measured size of paper over the loaf on said elevator, means for feeding the loaf forward from above said elevator, means for folding 50 various end and bottom flaps before said loaf feeding means operate, front end flap folders provided with heating means and between which said loaves are successively delivered by said loaf feeding means before the bottom end flaps are folded, bottom end flap 55

folders provided with heating means and between which each loaf is subsequently delivered, and a positively actuated heated roller operating on the bottom of the loaf adjacent said bottom end flap folders.

8. In a device of the character described, a vertically reciprocating elevator, a source of paper supply, means for feeding a measured size of paper over the loaf on said elevator, means for feeding the loaf forward from above said elevator, means for folding various end and bottom flaps before said loaf feeding means operate, front end flap folders provided with heating means and between which said loaves are successively delivered by said loaf feeding means before the bottom end flaps are folded, bottom end flap folders provided with heating means and between which each loaf is subsequently delivered, and oscillating heating means operating on the bottom of the loaf adjacent said bottom end flap folders. 75

9. In a device of the character described, a vertically reciprocating loaf-elevator, means for feeding a wrapper in position over the loaf on said elevator, means for folding rear end flaps, a rear bottom flap and a front bottom flap of the wrapper on said loaf, means operating after folding of the rear end and the rear bottom flaps to feed the loaf forwardly through the machine from the elevator and past the front bottom flap folding means, front end flap folders provided with heating means and between which the loaf is delivered, bottom end flap folders provided with heating means and between which the wrapped loaf is subsequently delivered and finally sealed, and independent heating means operating on the bottom of the wrapped loaf simultaneously with the heating means on said bottom end flap folders. 80

10. In a device of the character described, a vertically reciprocating elevator, a source of paper supply, means for feeding a measured size of paper over the loaf on said elevator, means for feeding the loaf forward from above said elevator, means for effecting various end and bottom folds before said loaf feeding means operate, front end flap folders provided with heating means and between which said loaves are successively delivered by said loaf feeding means before the bottom end flaps are folded, bottom end flap folders provided with heating means and between which each loaf is subsequently delivered, and independent heating means crowned longitudinally and operating on the bottom of the loaf adjacent said bottom end flap folders. 110

11. In a device of the character described, a vertically reciprocating loaf-elevator, means for feeding a wrapper in position over the loaf on said elevator, means for folding a rear end flap, a rear bottom flap, 115

- and a front bottom flap of the wrapper on said loaf, a front end flap folder provided with a first heating means and arranged to operate on the wrapper after the operation 5 of the rear end and rear bottom flap folding means, a bottom end flap folder provided with a second heating means and operating on the wrapper after the front end flap has been folded, and means for feeding the loaf 10 past the front bottom flap folder, the front end flap folder, and said bottom end flap folder.
12. In a device of the character described, a vertically reciprocating loaf-elevator, 15 means for feeding a wrapper in position over the loaf on said elevator, means for folding a rear end flap, a rear bottom flap, and a front bottom flap of the wrapper on said loaf, a front end flap folder provided with a 20 first heating means and arranged to operate on the wrapper after the operation of the rear end and rear bottom flap folding means, a bottom end flap folder provided with a second heating means and operating on the 25 wrapper after the front end flap has been folded, means for feeding the loaf past the front bottom flap folder, the front end flap folder, and said bottom end flap folder, and a third heating means disposed adjacent the 30 bottom end flap folder and operating on the bottom of the wrapped loaf simultaneously with the heating means of the bottom end flap folder.
13. In a device of the character described, 35 a source of paper supply, means for feeding a measured size of paper over the loaf to be wrapped, means for folding the end flaps, heating means engaging the same at the ends of the loaf, a movable heating roller 40 engaging the bottom of the loaf, a source of power, and connections between said source of power and the movable heating roller for positively actuating the latter.
14. In a device of the character described, 45 a source of paper supply, means for feeding a measured size of paper over the loaf to be wrapped, means for folding the end flaps, heating means engaging the same at the ends of the loaf, a movable heating roller crowned 50 longitudinally and engaging the bottom of the loaf, and mechanism for oscillating said roller.
15. In a device of the character described, 55 a source of paper supply, means for feeding a measured size of paper over the loaf to be wrapped, a pair of spaced heating plates for each end of the loaf, movable folding means for making various end and bottom folds before the loaf reaches the first heating 60 plates, stationary folders for completing the end and bottom folding before the second heating plate is reached, and an oscillating heated roller engaging the bottom of a wrapped loaf after the operation of said 65 folders thereon.
16. In a device of the character described, a source of paper supply, means for feeding a measured size of paper over the loaf to be wrapped, a pair of spaced heating plates for each end of the loaf, movable folding means 70 for making various end and bottom folds before the loaf reaches the first heating plates, stationary folders for completing the end and bottom folding before the second heating plate is reached, a delivery, and a 75 reciprocating member moving said loaves from said first heating plate to a position intermediate said plates, then to the second heating plates and then to the delivery.
17. In a device of the character described, 80 a source of paper supply, means for feeding a measured size of paper over the loaf to be wrapped, a pair of spaced heating plates for each end of the loaf, movable folding means for making various end and bottom 85 folds before the loaf reaches the first heating plates, stationary folders for completing the end and bottom folding before the second heating plate is reached, a delivery, and a reciprocating and vertically moving carriage 90 for progressing the loaves step by step from the first heating plates to the delivery.
18. In a device of the character described, a source of paper supply, means for feeding a measured size of paper over the loaf 95 to be wrapped, a pair of spaced heating plates for each end of the loaf, movable folding means for making various end and bottom folds before the loaf reaches the first heating plates, stationary folders for completing the end and bottom folding before the second heating plate is reached, a delivery, and a reciprocating and vertically moving carriage provided with rigid 100 depending fingers forming compartments for 105 the loaves progressing the loaves from the first heating plate to the delivery.
19. In a device of the character described, a source of paper supply, means for feeding a measured size of paper over the loaf 110 to be wrapped, a pair of spaced heating plates for each end of the loaf, movable folding means for making various end and bottom 115 folds before the loaf reaches the first heating plates, stationary folders for completing the end and bottom folding before the second heating plate is reached, a delivery, a reciprocating carriage progressing the loaves from the first heating plate to the delivery, and a vertically movable support 120 on which said carriage reciprocates.
20. In a device of the character described, an elevator for raising the loaves to be wrapped, a carrier reciprocating longitudinally of the machine and removing the loaf 125 from above said elevator, a second independent reciprocating carrier moving the loaf forward from the point of delivery by the first carrier, a vertically movable support on which said second carrier is slidably mount- 130

- ed, means raising and lowering said support at predetermined intervals, and means for reciprocating the second carrier on its vertically movable support.
21. In a device of the character described, an elevator for raising the loaves to be wrapped, a carrier reciprocating longitudinally of the machine and removing the loaf from above said elevator, and a second independent reciprocating carrier moving the same forward from the point of delivery by the first carrier, said second carrier being provided with a plurality of rigid downwardly extending arms forming compartments for the loaves.
22. In a device of the character described, an elevator for raising the loaves to be wrapped, a carrier reciprocating longitudinally of the machine and removing the loaf from above said elevator, a second independent reciprocating carrier moving the same forward from the point of delivery by the first carrier, said second carrier being provided with a plurality of rigid downwardly extending arms forming compartments for the loaves, and means for adjusting said arms toward and from each other.
23. In a device of the character described, a flap folder carriage, a carrier slidably mounted on said flap folder carriage and provided with rigid arms forming compartments for the loaves, means for reciprocating said loaf carrier to move the loaves step by step through the machine, and means for lowering and raising the flap folder carriage to engage the loaf carrier with and disengage the same from the loaves.
24. In a device of the character described, the combination of a vertically reciprocating carriage, an end folder mounted thereon and movable therewith, a carrier for the loaves mounted on said carriage for movement toward and away from the same, and means for reciprocating said carrier longitudinally of the machine.
25. In a device of the character described, the combination of an elevator, a vertically reciprocating carriage, a longitudinally reciprocable carrier movable with said carriage, and common means for operating said elevator and carriage.
26. In a device of the character described, the combination of an elevator, a vertically reciprocating carriage, a longitudinally reciprocable carrier movable with said carriage, an end folder for the wrapper also movable with said carriage, and common means for operating said elevator and carriage.
27. In a device of the character described, the combination of a rear bottom flap folder, a movable support therefor, an end flap folder movably mounted on said support in proximity to the bottom flap folder, means for imparting translatory movement to said support and folders, and means for moving said rear flap folder toward and away from the bottom flap folder.
28. In a device of the character described, the combination of a bottom flap folder, an end flap folder pivoted on said bottom folder, a movable support on which the bottom folder is mounted, and means for moving the end folder toward and away from the bottom folder during movement of the latter by its support.
29. In a device of the character described, the combination of a rear end flap holder, and means for moving the same in one plane to make the fold and in another plane to crease the fold.
30. In a device of the character described, the combination of a rear end flap folder, and a cam for guiding the same in two planes to make the fold and crease the same.
31. In a device of the character described, the combination of a rear end flap folder, means for reciprocating the same, and a cam for guiding the folder in two planes to make the fold and crease the same.
32. In a device of the character described, the combination of a rear bottom flap folder, a rear end flap folder, common means for reciprocating the same, and means for moving one folder relatively to the other during their reciprocating movement.
33. In a device of the character described, the combination of a rear bottom flap folder, a rear end flap folder, common means for reciprocating the same, and means for engaging the latter folder with the wrapper while it is supported by the former.
34. In a device of the character described, an end flap folder, a reciprocating structure on which said folder is mounted, means for reciprocating said structure, a loaf-carrier slidably mounted on the reciprocating structure for movement substantially at right angles thereto, and means for reciprocating said loaf-carrier.
35. In a device of the character described, a pair of heating plates provided with recesses, means for folding the front and rear end flaps, and means for moving the loaf between said plates and having fingers adapted to engage in said recesses.
36. In a device of the character described, the combination of a loaf-elevator, downwardly projecting fingers receiving the loaf from the elevator, means for raising and lowering said fingers, a gripping device automatically moved into engagement with the loaf when the same is positioned between said fingers, and a loaf-pusher movable past said gripping device and adapted to be reciprocated between the elevator and the loaf receiving fingers when the latter are raised.
37. In a device of the character described,

the combination of a loaf-elevator, downwardly projecting fingers arranged to receive a loaf from the elevator and adapted to resiliently engage said loaf, means for imparting raising and lowering movements to said loaf receiving fingers at predetermined intervals, other fingers moved into yielding engagement with the loaf when the same is positioned between the loaf receiving fingers, and a loaf-pusher movable past said last named fingers and adapted to be reciprocated between the elevator and the loaf receiving fingers when the latter are raised.

38. In a device of the character described, the combination of means for forming the front and rear end folds, heating plates engaging both of said folds, a finger pressing on said folds before the bottom end flap is sealed, means for folding the bottom end flap, and other heating plates for sealing the same.

39. In a device of the character described, the combination of means for partially wrapping a loaf or the like to form overlapping bottom flaps and rear end folds, means for thereafter forming front end folds and provided with heating means for sealing said front end folds to the rear end folds, means holding said sealed folds in place, means for subsequently folding bottom end flaps on the previously folded and sealed end flaps to complete the wrapping operation, and other heating means for finally sealing the wrapped article.

40. In combination, a vertically movable flap folder carriage, a loaf carrier slidably mounted thereon, heating means past which the wrapped loaf is progressed by said loaf carrier, a continuously moving delivery mechanism, and means for imparting variable speed thereto.

41. In combination, a loaf pusher, heating means between which the wrapped loaf is delivered by said pusher, a variably speeded delivery mechanism, a vertically movable flap folder carriage, and a reciprocating loaf carrier on said flap folder carriage for moving said wrapped loaf into engagement with said delivery mechanism.

42. In combination, a pusher, heating means between which the wrapped loaf is delivered by said pusher, a delivery mechanism spaced from the heating means, a vertically movable support, a loaf carrier reciprocating on said support for moving said wrapped loaf into engagement with the delivery mechanism, and means raising and lowering the movable support at predetermined intervals for imparting like movements to the loaf-carrier as the same is reciprocated.

43. In a device of the character described, the combination of a source of paper sup-

ply, means for feeding a measured size of paper over the loaf to be wrapped, a vertically reciprocating folder operating to fold the first end flap on one side of the loaf, a rear bottom flap holder, folding mechanism operating to fold a second end flap while the loaf rests on the bottom folder, and other folders to fold the remaining end flaps.

44. In a device of the character described, a source of paper supply, means for feeding a measured size of paper over a loaf or the like to be wrapped, means for initially associating the loaf with the wrapper, means for feeding the loaf with the wrapper thereon forwardly through the machine, means for folding various end and bottom flaps prior to the operation of said loaf feeding means, front end fold formers provided with heating means and between which the loaf is delivered by said loaf feeding means, and bottom end fold formers provided with heating means and between which the loaf is subsequently delivered to complete the wrapping and sealing operations.

45. In a device of the character described, a source of paper supply, means for feeding a measured size of paper over a loaf or the like to be wrapped, means for initially associating the loaf with the wrapper, means for feeding the loaf with the wrapper thereon forwardly through the machine, means for folding various end and bottom flaps prior to the operation of said loaf feeding means, front end fold formers provided with heating means and between which the loaf is delivered by the loaf feeding means, bottom end fold formers provided with a second heating means and between which the loaf is subsequently delivered to complete the wrapping operation, and a third heating means operating on the bottom of the wrapped loaf and disposed adjacent said bottom end fold formers.

46. In a device of the character described, a source of paper supply, means for feeding a measured size of paper over the loaf to be wrapped, means for feeding the loaf forward through the machine, means for folding various end and bottom flaps before said feeding means operate, front end fold formers provided with heating means and between which said loaves are successively delivered by said loaf feeding means, bottom end fold formers provided with a second heating means and between which each loaf is subsequently delivered, and a third oscillating heating means operating on the bottom of the loaf adjacent said bottom end fold formers.

In testimony whereof I have signed this specification.

OSCAR SANDBERG.
